UNITED STATES PATENT OFFICE.

WILLIAM HENRY CLAYTON, OF VILLA RICA, GEORGIA.

SEWING-MACHINE MOTOR.

SPECIFICATION forming part of Letters Patent No. 364,216, dated June 7, 1887.

Application filed October 20, 1886. Serial No. 216,747. (No model.)

To all whom it may concern:

Be it known that I, WILLIAM HENRY CLAYTON, a citizen of the United States, and a resident of Villa Rica, in the county of Carroll and State of Georgia, have invented certain new and useful Improvements in Sewing-Machine Motors; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of a side elevation. Fig. 2 is an end elevation, partly in section; and Fig. 3 is a detail view.

My invention relates to sewing-machine motors; and it consists in the construction and novel combination of parts, as hereinafter described and claimed.

Referring to the accompanying drawings, 2 designates the frame of the motor, said frame being suitably braced to give it the necessary strength. The frame 2 is provided with feet 12 and 13, through which screws are passed into the stand or other support, upon which the motor is mounted to give it the necessary elevation with reference to the machine to be driven thereby.

17 is a horizontal bar, in which the shaft of the driving-gear 16 is journaled, said shaft projecting laterally from the bar 17. The shaft 18 of the driving-gear 16 is provided with a worm-wheel, 19, which is engaged by a worm-pinion, 20, on the winding-shaft 11, which shaft 11 is supported in bearings in hangers 22 and 23, depending from the horizontal bar 17, and is movable longitudinally in its bearings to permit the worm-pinion to be thrown in and out of gear with the worm-wheel 19.

The worm-wheel 19 is provided with a coil-spring, 24, one end of which is connected to the said wheel, and the other end to the shaft 18, upon which shaft the spring is coiled when the winding-shaft is operated to wind the motor.

The teeth of the driving-gear 16 engage the teeth of the large gear-wheel 3, which is jour-

naled on a shaft secured in the frame of the motor. The large gear-wheel 3 engages a pinion, 7, on the shaft of the gear-wheel 4, and the gear-wheel 4 engages the teeth of the gear-wheel 6 on the pulley-shaft 15, journaled in the 55 depending arm 26 of the frame, near the lower end of said arm 26. The curved arm or regulating-lever 28 is pivoted to the depending arm 26, and to arm 28, near its lower end, is secured a curved arm, 27, in the upper end of 60 which is journaled the shaft 15. The said arm 26 is practically a spring-arm, and it may be deflected sufficiently, by means presently described, to adjust the wheel 6 into and out of gear with the large wheel 4. The pulley 25 65 on shaft 15 is connected by a belt, 30, with a small pulley, 31, on the sewing-machine.

The regulating-lever is operated by a threaded cranked rod, 9, which is seated in the lever near its lower end, and is seated, also, 70 in the short upright 34 of the frame of the motor, so that said lever may be moved in and out by said crank-rod 9 to start or stop the sewing-machine.

Having described my invention, what I claim 75 as new, and desire to secure by Letters Patent, is—

In a sewing-machine motor, the combination of the main frame having a standard provided with a depending yielding arm, 26, a 80 curved regulating-lever, 28, provided with an adjusting device at its lower end and secured to said arm 26, an arm, 27, pivoted to lever 28, a shaft, 15, journaled in the arm 26 and 27, and bearing a pinion and a pulley, a wheel, 85 4, adapted to engage with the teeth of pinion 6, and applied on a shaft bearing a spur-wheel, 7, engaging with a spur-wheel, 3, a spur-wheel, 16, engaging with wheel 3, and keyed on shaft 18, a worm-wheel also applied on this shaft and 90 provided with a driving-spring, and a worm-pinion keyed on an endwise-adjustable winding-up shaft, all constructed and adapted to operate substantially as described.

In testimony whereof I affix my signature in 95 presence of two witnesses.

WILLIAM HENRY CLAYTON.
